UNITED STATES PATENT OFFICE.

HECTOR J. LUCIER, OF STOUGHTON, MASSACHUSETTS.

COMPOSITE HEEL FOR BOOTS AND SHOES.

Application filed February 7, 1921. Serial No. 443,045.

To all whom it may concern:

Be it known that I, HECTOR J. LUCIER, a citizen of the United States, resident of Stoughton, in the county of Norfolk and 5 State of Massachusetts, have made a certain new and useful Invention in Composite Heels for Boots and Shoes; and I declare the following to be a full, clear, and exact 10 description of the same, such as will enable others skilled in the art to which it appertains to make and use the invention, reference being had to the accompanying drawings, and to letters or figures of reference marked thereon, which form a part 15 of this specification.

The invention has relation to rubber heels for boots and shoes, and it consists in the novel construction and combinations of parts as hereinafter set forth.

20 In the manufacture of boots and shoes, it is frequently desirable to apply rubber heels to them during the manufacturing operation, so that when the boot or shoe is completed it is provided with a rubber 25 heel instead of with a leather heel. In so making boots and shoes, it is common practice to employ a heel made entirely of rubber and provided with a concave upper face to fit the heel seat portion of the shoe. Such 30 a heel is referred to in the trade as a "whole" heel.

It is also common practice to provide a shoe with a rubber heel having a less thickness than the entire height of the heel and 35 commonly referred to as "half" heels. These "half" heels are usually made with a flat top surface and in order to apply them to a shoe, it is necessary to build a base of leather or its equivalent on the heel seat 40 portion of the shoe to form a proper support for the attachment of the half heel.

The operation of attaching either a whole heel or a half heel to a shoe involves the step of cementing the heel either to the 45 heel seat portion of the shoe or to said leather base, and this cementing operation requires a certain length of time for the cement to set or dry, and therefore when the heel is attached to the shoe during the process 50 of manufacture, the shoe must of necessity be laid aside for a time while the cement is drying. This delays the manufacturing operation and also necessitates the use of considerable storage space for 55 the shoes while the heel cement is drying.

The use of a whole heel of rubber is

not always satisfactory, because of the difficulty of making a good joint where the top peripheral edge of the heel meets the edge of the heel seat portion of the shoe. A rubber heel is more or less elastic and yielding, and because of the fact that the heel seat portions of different shoes vary somewhat in contour, it is not always possible to attach the heel to the shoe so as to provide a permanently tight joint between the rubber and the heel seat portion of the shoe. For 60 this reason there are some advantages in the half heel, with its leather base, because the leather base can be made so that it 65 will always make a tight joint with the heel seat portion of the shoe, and one which will be invisible and will not open as the shoe is used. Moreover, since rubber is considerably heavier than leather, the half heel 70 with its leather base weighs considerably less than a whole heel of rubber, and this 75 is also an advantage.

It is one of the objects of this invention to provide a composite rubber and leather 80 heel which can be manufactured separately from the shoe and can be applied to the shoe by a nailing process and without the necessity of going through the operation of cementing the heel to the shoe, with the consequent loss of time required for the cement to dry, and which also has the advantages 85 of the half heel above recited.

Other novel features or objects will be more particularly pointed out in the following description of a selected embodiment of my invention.

In the accompanying drawings, illustrating an embodiment of the invention:

Figure 1 is a central longitudinal section 95 of the invention as applied.

Figure 2 is a perspective view of the invention, with the leather lift partly in section.

Figure 3 is a section on the line 3—3, Figure 1.

Figure 4 is a detail central longitudinal section of the leather lift.

Figure 5 is a similar view of the rubber heel.

Figure 6 is a sectional view of the invention, similar to the showing of Figure 3, but before attachment to the shoe.

In these drawings the numeral 1 designates a heel body of rubber or rubber compound, and 2 is a top lift of leather or leather substitute. The heel body 1 is mold-

ed to the desired shape, and is of less thickness than the complete or "whole" heel and of greater thickness than the "half" heel. The heel body 1 is molded with its top face 5 concaved in scoop fashion, as will be noted from the longitudinal and transverse sections shown in the drawings, and the leather lift 2 has its top face 6 concaved also in scoop fashion, as will be noted from the 10 drawings, and conforms approximately to the curved shape of the heel seat portion of the shoe.

If it were attempted to have the lift 2 of uniform thickness throughout, with its top 15 face concaved as above stated, the top face of the rubber body 1 would, for a proper concavity to fit the heel seat portion of the shoe, have to be concaved to such an extent as to reduce said body so much in thickness 20 that it would interfere with the washers 5, and if it were attempted to form the concavity in the top face of the leather top lift 2 alone, leaving the top face of the rubber body 1 flat or plane, said top lift would be 25 reduced to a rand formation, which is common practice today and which would sacrifice an advantage of the leather top lift 2 in that it is relatively stiff and serves to hold the rubber body or heel proper from undue 30 spreading when it is applied to the shoe.

Applicant therefore makes the concave top face 6 of the lift 2 the sum of the concavity of said top face and of the concavity of the top face 3 of the rubber body, the curvature 35 of the lower face 7 of the lift 2 being such, relative to the curvature of the face 6, that the lift is thinner at the middle than at the edges thereof. The convexity of the said lower face 7 is of the same degree as the concavity of the upper face 3 of the rubber body 1.

The bottom or wear face 4 of the rubber body 1 is formed slightly convex transversely of the heel, and especially at the 45 breast of the heel, said convexity being of less degree than that of the concavity 3. Said body is provided with the usual washers 5, imbedded therein for the purpose of receiving or backing up the heads of the 50 nails by which the heel is secured to the shoe.

The lift 2 is of leather or leather substitute, being of a material that can be molded or formed into the desired shape either in- 55 dependently of the rubber body 1 or in the same mold as said body, and which will re-

tain such shape. The top face 6 of the lift 2 has its curvature of greater rather than less degree than the curvature of the heel seat portion of the shoe, whereby the driving of 60 the nails through the holes or washers adjacent to the breast of the heel will flatten the lift 2 slightly in conforming it to the shape of the heel seat portion of the shoe, and will press the peripheral or outer edges of said 65 lift firmly against the outer edges of the said heel seat portion. In driving the nails as stated to flatten the top section 2, the convex portion or convexity of the wear face 4 of the heel body will be flattened, so that the 70 heel will have a flat wear face when secured to the shoe.

When the composite heel is nailed to the shoe it is necessary that the leather top lift 2 shall be trimmed off marginally, to make a 75 neat and tight or flush joint with the inner-sole 8 of the shoe to which it is nailed, and for this purpose said top lift is extended marginally of the rubber body 1, except at the breast of the heel, this marginal exten- 80 sion being shown at 9. In order that the marginal extension 9 shall be capable of being trimmed off to the best advantage in making a flush joint as stated, the peripheral edge 10 of said extension is made normally 85 vertical, this being of advantage also in avoiding a groove or any trace of a groove between the rubber body 1 and the inner sole 8, along the upper edge of the lift 2, as thereby a greater margin of safety is pro- 90 vided. A further advantage of the marginal extension 9 is that any tendency of the rubber body 1 to spread or expand peripherally when nailed to the shoe, to leave a groove or trace of groove between said rubber body 95 and the innersole 8, along the lower edge of the lift 2, is avoided.

I claim:

As a new article of manufacture, a composite heel for boots and shoes comprising a 100 rubber body having a concave scoop-shape upper face and a leather top lift having a concave upper face and a convex lower face cemented to the upper face of said body, said lift being thinner at the middle than at 105 the edges thereof.

In testimony whereof I affix my signature, in presence of two witnesses.

HECTOR J. LUCIER.
